ILLUMINABLE NOTE PAD HOLDER
OR THE LIKE

Jerome S. Wittenberg, 659 Eagle Rock Ave.,
West Orange, N.J. 07052

Filed Jan. 16, 1967, Ser. No. 5,434

Term of patent 14 years

(Cl. D74—9)

Fig. 1

Fig. 3

Fig. 2

Fig. 4

Fig. 5

FIGURE 1 is a view in perspective of an illuminable note pad holder or the like, showing my new design;

The bottom is plain.

I claim:

The ornamental design for an illuminable note pad holder or the like, substantially as shown and described.
